UNITED STATES PATENT OFFICE.

MAURICE S. FINCH, OF ST. JOSEPH, MISSOURI, ASSIGNOR TO SPECIALTY SHOE MACHINERY COMPANY, OF ST. JOSEPH, MISSOURI, A CORPORATION OF MISSOURI.

MACHINE FOR FEEDING AND DRIVING NAILS.

1,401,767.

Specification of Letters Patent. Patented Dec. 27, 1921.

Application filed July 11, 1919. Serial No. 310,270.

To all whom it may concern:

Be it known that I, MAURICE SMITH FINCH, a citizen of the United States, residing at St. Joseph, in the county of Buchanan, State of Missouri, have invented certain new and useful Improvements in Machines for Feeding and Driving Nails, of which the following is a complete specification.

10 The present invention relates to nailing machinery, and has for its general object to provide an improved type of machine adapted for use in the driving of nails into the soles or heels of boots and shoes.

15 In general, the invention comprises a machine having nail driving mechanism and a suitable work support for positioning the boot or shoe in proper relation to said driving mechanism, together with a hopper receptacle for retaining a supply of the nails, and automatic means for feeding the nails as fast as required to the driving mechanism.

20 One of the features of the improvements comprises a novel feeding mechanism operated from a reciprocating nail driving mechanism and so constructed and arranged as to obtain a substantially continuous feeding action derived from both the reciprocatory movements of said driving mechanism. Improvements are also provided in the specific character of the nail feeding mechanism whereby a novel and efficient mode of feeding operation is effected, characterized by 25 improved means for assembling the nails in the raceway, novel means for preventing any overloading of the raceway, and also an improved construction for presenting and retaining the nails in their proper position 30 for the driving operation. Provision is also made for preventing injury to the parts of the nail feeding mechanism whenever the latter becomes clogged, by introducing a safety feature permitting the continued operation of the nail driving mechanism while 35 allowing interruption of the nail feeding drive whenever the action of the latter is obstructed.

40 With these general objects in view, as well as minor objects which will appear in the course of the detailed specification, the invention will now be described with reference to the accompanying drawings illustrating a construction embodying the improvements and designed particularly for

operation in the driving of what are known as hob nails, after which the novel features of the same will be set forth and defined in the appended claims.

In the drawings—

60 Figure 1 is a side elevation of a nailing machine constructed in accordance with the present invention, with parts of the framework broken away;

Fig. 2 is a front elevation of the same, 65 with a portion thereof broken away;

Fig. 3 is an enlarged side elevation of the head of the machine;

Fig. 4 is a plan view of the same;

Fig. 5 is a plan view of the nail hopper, 70 looking at the same in line with its axis and with a portion of the rotary disk broken away;

Fig. 6 is a rear view of the head of the machine;

Fig. 7 is a vertical sectional view taken 75 on the line 7—7 of Fig. 4;

Fig. 8 is a detail view showing parts of the drive to the nail feeding mechanism;

Fig. 9 is a section taken on the line 9—9 80 of Fig. 6;

Figs. 10, 11 and 12 are enlarged detail views of a portion of the nail raceway, Fig. 12 showing an altered position of the parts to illustrate the action of the movable section of said raceway for interrupting the feed from the hopper, as hereinafter explained;

Fig. 13 is a vertical section taken on the line 13—13 of Fig. 4; and

90 Figs. 14 and 15 are detail sections taken on the lines 14—14 and 15—15, respectively, of Fig. 13.

95 Referring now to the drawings in detail, these illustrate the improved construction in connection with the usual form of supporting column or casting 16 carrying a fixed overhanging bracket 18 provided with a bearing guide 20 in alignment with a bearing 22 at the top of the casting 16, and a third bearing 24 arranged inside said column or casting 16, these three bearings being for the purpose of accommodating a vertically reciprocating bar 26 by which the nail feeding and driving operations are effected, as hereinafter described. The lower end of the bar 26 is connected by a rod 28 to a foot treadle 30 mounted in the base of the column 16 (Fig. 1) and held normally elevated by means of a strong coil spring 32 110

which is suspended from a retaining element 34 in the upper part of said column. The upward movement of the bar 26 is limited by the bearing 24, for which purpose the bar 5 is provided with a collar 36 beneath said bearing, a leather buffer 38 being inserted between said collar and bearing.

Associated with the upper end of the bar 26 is a head member 40 which is provided 10 with bearing portions 41 and 42 slidably engaging said bar intermediate the bearings 20 and 22, and also with a bearing lug 43 engaging an upright pin 44 at the top of the column 16 (see Figs. 1 and 3), thereby 15 confining the movement of said head member to a vertical reciprocating motion. The bar 26 is provided with a collar 46 adapted, on said bar's being lifted by the action of the spring 32, to engage the bearing 41 of 20 the head member 40 and lift the latter into raised position off the top of the column 16, as shown in Figs. 1 and 3, whereas lowering of the treadle 30 allows the head member to come to rest by gravity upon the top of 25 said column.

The parts comprising the nail feeding mechanism will now be described. A nail receiving hopper is formed by a cylindrical shell 48 fitting frictionally over the upper 30 and outer margin of a hopper bottom casting 50 provided with a lug 51 which is attached by bolts 52 to an angular projection 53 at the top of the head member 40, the arrangement being such as to support the 35 hopper in outwardly inclined relation at the top of the machine, in which position the nails tend by gravity to occupy the lower side of the hopper and are fed by the action of the feeding means to the raceway which 40 communicates with the upper side of the hopper. Mounted within the hopper upon the upper face of the bottom casting 50 is a rotary nail feeding disk 54 provided with a series of upwardly extending nail engaging pins 55, the outer portion of the disk's 45 surface being also broken by a series of perforations 56 for engagement with the nails. (See Figs. 4 and 5.) The disk 54 is also formed with a series of peripheral notches 57 slightly smaller than the heads 50 of the nails 58 and extending inward at an angle to the disk's radius, or backward with reference to the direction of rotation of said disk. The rear sides of the notches 57 (with 55 reference to the direction of travel) are elevated slightly above their forward sides (Fig. 3) and the disk is also cupped out slightly around the inner ends of the notches 60 (see Fig. 11) for providing an easy gliding passage into the notches for the nails 58 which are designed to be trapped by said notches. The disk 54 rotates with its notched periphery riding over an annular channel 59 in which the shanks of the nails are suspended when their neck portions are engaged

within the notches, as illustrated in Fig. 7. The shell 48 carries a radially projecting baffle plate 60 overlying the upward path of the nails as they approach the mouth of the raceway, this plate being provided with 70 a restricted opening 61 allowing passage of the nails only at the outer margin of the hopper in line with the channel 59. A pair of flexible wire fingers 62 are positioned partly across the opening 61 to assist in 75 spreading the nails as well as aiding in engaging them with the notched portions of the disk. It will also be noted that the outer portion of the hopper bottom casting 50 has a sloping margin as indicated in Fig. 7, 80 which operates to deflect the nails into engaging relation with the disk notches, and along the upper portion of this sloping margin the same is fitted with a tapered rib 63 at the final approach to the raceway (see 85 Fig. 5), this rib acting in conjunction with said sloping margin to lift the nails and switch them over on to the disk's periphery and affording them a final opportunity to become seated in the notches 57 and channel 59.

The disk 54 is suitably secured to the upper end of a short shaft 64 which is journaled in the hub portion 65 of the hopper bottom casting 50 (Fig. 7). The lower portion of 95 this shaft 64 has secured thereto a ratchet wheel 66 on the opposite sides of which a pair of split collars 67 are loosely mounted, and each of the collars 67 carries a pawl 68 actuated by a spring 69 into engagement with the teeth of the ratchet wheel 66; each collar 67 also carries a bevel gear segment 70, the two segments 70 being in mesh with opposite sides of a bevel pinion 71 journaled on the end of a post 72 depending from the casting 50. The lower split collar 67 is secured fast to the hub portion of a third gear segment 73 which in turn is loosely journaled on the lower end of the shaft 64 and retained thereon by a collar 74. The gear segment 73 meshes with a gear segment 75 loosely mounted between a pair of friction washers 76 on a stub shaft 77 carried by the head member 40. One of the friction washers 76 is in engagement with the bearing portion of a rocker arm 78 carried by the inner end of the stub shaft 77, while the other washer 76 is embraced by a clamping washer 39, the clamping force being applied by a nut 79 screwed on to the outer end of 120 said shaft 77, after which the washer 39 may be fixed by a set screw 39'. A pin 80 engages a slot 81 in the segment 75 for positioning and limiting the movements of the latter. The rocker arm 78 is provided with 125 one or more slots 82 (see Fig. 3) for engaging a pin 83 carried by an arm 84 secured to the collar 46 on the bar 26, said arm being adjustably secured to said nut by means of a screw 85 and a pin 86 fitting in 130

openings 87 of said nut. By means of this construction it is apparent that the throw of the arm 78 may be adjusted to vary the feeding action which is effected by the rotation of the disk 54 by means of the described connections, and that this rotation is made substantially continuous for both the up and down movements of the bar 26, since the gear segments 70 operate alternately through the 10 pawls 68 to advance the ratchet wheel 66 for each stroke of said bar 26.

That portion of the nail feeding mechanism which acts to transfer the nails from the hopper to the raceway leading to the 15 driver will now be described, reference being had more particularly to Figs. 10 to 12. At the upper side of the hopper and at a point in the path of the nails just after they have begun their downward movement with the 20 disk 54, an opening 88 is provided in the side margin of the hopper bottom casting 50 for the mouth of the raceway, in which opening elements are arranged to form a switch passage for deflecting the nails from the 25 hopper disk 54 into the raceway, one of these elements being the enlarged end of the rib 63 and the other of said elements being a switch finger 89. This switch finger 89 is carried by a tilting section 90 of the raceway 30 which is pivoted at 91 to a lug 92 (see Fig. 1) depending from the base of the hopper. The switch finger 89 operates alongside a fixed finger 93 projecting inside the hopper in overhanging relation to the edge of the 35 disk 54, said finger 93 assisting in shielding the opening into the raceway and also serving as a reinforcing bearing for the free end of the finger 89. Extending along the channel 59 underneath the rib 63 is a slender 40 spring 94 which engages the shanks of the nails 58 and operates to retain the same snugly seated in the notches 57 as they approach the switch passage. The tilting raceway section 90 is incased between two housing sections 95 secured to lugs 96 formed on the hopper base at opposite sides of the raceway, and one of the sections 95 carries a leaf spring 97 overlying the tilting section 90 and projecting through the opening 88 45 for the purpose of steadyng and directing the movements of the nails as they are switched into the raceway, and also retaining the same in position on the tilting section 90. Normally the tilting section 90 is held 50 in elevated position opposite the opening 88 by means of an arm 98 carrying a counter-weight 99, as shown in Fig. 10, and is latched in this position by means of a latch element 100 pivoted at 101 to the housing sections 95 and provided with a notch 102 engaging a pin 103 carried by said tilting section 90. In the switching operation, the 55 nails are deflected from the notches 57 by the means above described on to the tilting section 90, the shanks of the nails passing

through a narrow passage 104 (see Figs. 5 and 11) in the hopper base, with which passage each of the notches becomes momentarily registered during the rotation of the disk 54. The succeeding nails push those 70 ahead of them on down the track comprising the raceway section until the same becomes loaded, whereupon the advance nail is pressed against a finger 105 which is carried by the latch 100. The pressure upon the 75 finger 105 swings the latch 100, resulting in disengagement of its notch 102 from the pin 103, and as the load of nails carried by the tilting section is sufficient to overbalance the counterweighted arm 98, said section 90 tips 80 into the inclined position illustrated in Fig. 12, in which position the nails are discharged from the section 90 into the fixed raceway section 106 (i. e., fixed as regards any angular movement) which is supported in inclined position by a block 107, attached to the head member 40. In its tilted position the raceway section 90 is again latched by engagement of its pin with a second notch 108 on the lower end of the latch 100. While 85 the tilting section is thus latched in tilted position, the switch finger 89 is retracted from the hopper, as illustrated in Fig. 12, and the discharge of the nails from the hopper ceases until the tilting section returns 90 to raised position and said switch finger is again projected into operative position 95 within the hopper.

It is desirable to prevent overloading of the raceway, and the tilting section 90 is provided for this purpose, the same acting intermittently to replenish the supply in the fixed raceway section, and remaining in tipped position until its load has been completely discharged. The latch element 100, acting 100 as a gravity latch, is readily disengaged by the vibration of the machine, and consequently means is provided for positively locking said latch until the tilting section has completely discharged its load, this 105 means comprising a downward extension 109 from the finger 105, which extension 109 is presented at a level with the heads of the nails in the fixed raceway section 106 during the latching engagement of the pin 103 with the notch 108, and prevents disengagement of said pin and notch until all the nails have passed below the end of said extension 109, since the latch can not swing without depressing said extension into the raceway. 110 As soon as the upper end of the fixed raceway 106 is clear, however, said latch becomes disengaged by the jar of the machine, and the tilting section 90 is returned to original position by the action of its counter-weighted arm 98.

Referring now more particularly to Figs. 3, 4, 13 and 14, the fixed portion 106 of the nail raceway is shown as terminating at the upper face of the block 107, which is 130

provided with a slide passage 110 into which the nails are one by one discharged in front of a slide block 112 forming part of a nail separating mechanism which operates to transfer the nails from the raceway to a chute passage 113 (formed in an attachment 131 to the block 107) through which the nails gravitate to the nail driving means. The block 112 is reciprocated by means of an oscillating segment 114, provided with a nail receiving notch 114' and connected by a pin 115 with said block, said pin engaging in a slot 116 formed in the top of the block. The nails travel along the passage 110 with their heads supported by the notched portion of the segment 114 and their shanks depending into the passage 110, a curved guard element 111 being mounted around the top margins of said passage. The segment 114 is secured to the lower end of a rock shaft 117 supported in a step bearing in the block 107, the upper end of said shaft being retained by an angle bracket 118 secured to said block 107. The shaft 117 is rocked by means of a frictional drive connection which comprises a disk 119 loosely applied to the reduced upper end portion of said shaft and embraced by a pair of friction washers 120 which are clamped by keyed metal washers 121 and a clamp nut 122 to the opposite faces of said disk. The disk 119 is provided with a pin 123 carrying a roller 124 operating in an inclined roller guideway 126 which is attached to the nail driver arm 127 carried by the vertically reciprocating bar 26. Thus as the bar 26 is reciprocated in the driving operation, the segment 114 is oscillated by the rocking of the shaft 117, thereby reciprocating the block 112 to intermittently transfer the nails from the raceway to the chute passage 113.

The nail driving means comprises a nail driver rod 128 adjustably mounted in the arm 127 and clamped thereto by a nut 129, the lower end of said rod 128 being suitably recessed to conform to the shape of the nail heads. The rod 128 has a plunger movement through a passage 130 in the horizontal arm of the head member 40, beneath which passage is provided an expandible nail receiving throat formed in two sections 132 pivoted at 133 within a recess 134 in the head member. The sections 132 are formed with mating channels co-operating to provide a throat passage 135 for receiving the nails and the driver rod 128, said passage 135 communicating through an opening 136 in said sections (see Fig. 13) with the chute passage 113. The sections 132 are held normally together by springs 137, so that the passage 135 is thereby contracted to the size of the nail heads and driver. The lower end of said passage 135 is tapered so as to retain the nail until the descent of the driver forces it out, thereby

simultaneously spreading the sections 132 in an obvious manner.

The work into which the nails are to be driven is designed to be carried by a horn 140 of the usual type attached to the top 70 of a spindle 141 which is slidably mounted in a post 142 at the front of the column 16. This work support is of an adjustable character, the lower end of the spindle 141 being connected by a pivotal link 143 with a 75 foot lever 144 fulcrumed at 145 at one side of the column 16, and being provided at the other side of the column 16 with a pawl projection 146 engaging a ratchet plate 147. Lateral swinging motion is afforded the 80 lever 144 on its fulcrum 145 for disengaging the pawl 146 and adjusting it into different positions along the plate 147 and thereby varying the elevation of the horn, said pawl being held normally in engagement with the plate 147 by the action of a spring 148. A strong coil spring 149, operating between a shoulder 150 provided on the interior of the post 142 and a pin 151 on the spindle 141, tends to urge the latter 90 in a downward direction in opposition to the action of the lever 144.

For positioning the edge of the work with relation to the line of the nail driving operation, I provide an angular gage element 152 extending on a level with the space just below the mouth of the throat passage 135, which gage element 152 is carried by a rack bar 153 provided with a keyway 154 engaging a horizontal key 155 on one side 100 face of the horizontal arm of the head member 40, said bar being retained in sliding engagement with said key by a pair of bracket plates 156. Between these bracket plates 156, and projecting from the same face of the head member, is a pin 158 for journaling a gear 159 provided with an operating handle 160, said gear meshing with the teeth of the rack bar 153, whereby the latter with its gage element 152 may be readily shifted 110 to any desired position within the limits of the rack bar's movements.

A gage 161 is also provided for suitably gaging the spacing distance between the nails as they are driven, this gage being pivotally supported from a bracket plate 162 attached to the horizontal arm of the head member 40 on the side opposite thereof from the raceway, or on that side toward which the work is fed during the driving operation. The lower end of this gage 161 is on a level with the mouth of the throat passage 135, and is adapted to rest on the face of the work and abut against the edges of the nails after they are driven. This gage 120 is adjusted by means of a screw 163 extending through the gage and carrying a nut 164 by which the gage is forced up against a spring 165 which is coiled around the screw 125 between the gage and the head member 40. 130

The operation of the machine will be readily understood from the foregoing description, but the same may be briefly summarized as follows. The purpose of the machine, as illustrated, is especially designed for use in the driving of nails of the type shown, having a large head, into the soles or heels of boots or shoes of any type or material, such as leather or wood, or a combination of such materials. A quantity of the hob nails 58 are placed in the hopper, and the horn 140 is adjusted to the proper height according to the thickness of the stock, by means of the lever 144. The edge of the work is rested against the face of the gage 152, and this gage is adjusted according to the distance which it is desired to space the line of nails from the edge of the work. The treadle 30 is now depressed a sufficient number of times to obtain a supply of the nails in the raceway. The operation of this lever acts through the described connections to the hopper disk 54 to rotate said disk, and this rotation is substantially continuous, since the gear and ratchet elements are operated by both the up and down movements of the vertically reciprocating bar 26. One particular advantage of this feature of the construction is that a slower feeding movement of the 30 nails within the hopper is rendered possible by the practically continuous driving action, and hence there is less likelihood of the nails clogging and obstructing the feeding mechanism. The rotation of the disk feeds the 35 nails from the hopper into the tilting raceway section 90, which remains latched until said section is filled, and then automatically trips to discharge the nails into the fixed raceway section 106. Nails are now transferred from the lower end of the raceway by the action of the nail separating means above described, the oscillating segment 114 moving the nails one by one to the upper end of the chute passage 113, through which they 40 drop into the sectional throat 135 between each stroke of the driver 128. In the throat 135 the nail is held in position for the driver's action with the point of the nail almost in contact with the work at the moment the 45 driver's action begins. The driving operation is carried out by lowering of the treadle 30, the initial movement of which lowers the head member 40, bringing the tip of the sectional throat 135 against the stock, whereupon the continued movement of the lever or 50 treadle depresses the driver 128 and drives the nail, the throat sections 132 spreading apart to permit the discharge of the nail. After the first nail has been driven, the work 55 is moved to bring said nail up against the gage 161, which is adjusted according to the distance it is desired to space the nails apart, the work being then held with said driven nail against the gage 161 during the driving 60 of the next nail.

As soon as the fixed portion 106 of the raceway becomes filled, the tilting section 90 thereafter remains tilted by the action of the latch 100, until the nails have passed from beneath the finger 109 of the latch; the tilting section is then automatically released and returns to raised position to obtain a fresh supply of the nails, for which purpose the switch element 89 is again projected into operative position for deflecting the nails from the hopper into the mouth of the raceway. This interruption in the flow of the nails into the raceway prevents overloading of the raceway and results in a better and more even movement of the nails by preventing them from crowding each other or getting out of line and clogging in the raceway.

It is thus apparent that a practical and efficient construction has been provided for embodying the proposed improvements. An improved and substantially continuous nail feeding action is effected by the means shown, and this is accompanied by complete safety in the drive transmission, since the friction drive to the hopper disk 54 permits the continued operation of the reciprocating bar 26 without damage to the hopper feed in case said disk should become clogged by the nails at any point. The same safety provision takes care of any clogging of the nails at the point where they are transferred from the raceway to the nail driving mechanism, due to the frictional drive provided for the rocker shaft 117.

While I have illustrated and described what is now deemed to constitute the preferred form of embodiment of the invention, I desire to reserve the right to make all such formal changes or modifications as may fairly fall within the scope of the appended claims.

Having described the invention, what I claim is:

1. A nailing machine comprising a nail driving mechanism, a hopper provided therein with a rotary nail feeding disk, and means for intermittently rotating said disk including a ratchet wheel alternately actuated by a pair of interconnected and oppositely moving gear segments, one of said gear segments being oscillated from said nail driving mechanism.

2. A nailing machine comprising a nail driving mechanism, a hopper provided therein with a rotary nail feeding disk, a ratchet wheel operative to rotate said disk, a pair of spaced gear segments adapted to alternately actuate said ratchet wheel and provided with a gear pinion connecting said segments for movement in opposite directions, and means for oscillating one of said gear segments from said nail driving mechanism.

3. A nailing machine comprising a nail driving mechanism, a hopper provided

- 6
- therein with a rotary nail feeding disk having a shaft provided with a ratchet wheel secured thereto, a pair of spaced gear segments provided with pawls for alternately 5 actuating said ratchet wheel, a gear pinion connecting said segments for movement in opposite directions, and means for oscillating one of said gear segments from said nail driving mechanism.
- 10 4. A nailing machine comprising, in combination, a nail driving mechanism, a nail hopper, and a nail raceway connecting said hopper and driving mechanism and including a movable raceway section maintained 15 normally in position for receiving nails from the hopper and out of communicating relation with the remainder of the raceway, said movable raceway section being constructed and arranged to assemble a plurality 20 of nails from the hopper and be moved by the weight of such plurality of nails into communicating relation to the remainder of the raceway for discharging said assembled nails thereinto.
- 25 5. A nailing machine comprising, in combination, a nail driving mechanism, a nail hopper, and a nail raceway connecting said hopper and driving mechanism and including a tilting raceway section constructed 30 and arranged to receive nails from the hopper and be tilted by the weight of a plurality of nails into position to deliver them into the remainder of the raceway.
- 35 6. A mailing machine comprising, in combination, a nail driving mechanism, a nail hopper, a nail raceway connecting said hopper and driving mechanism and including a tilting raceway section communicating directly with the hopper, means for feeding 40 the nail's from the hopper into said tilting section, said tilting section tipping automatically after receiving a given number of nails to discharge the same into the remainder of the raceway and also operating to 45 interrupt the discharge of the nails by said feeding means from the hopper.
- 50 7. A nailing machine comprising, in combination, a nail driving mechanism, a nail hopper, a nail raceway connecting said hopper and driving mechanism and including a tilting raceway section communicating directly with the hopper, and means for feeding the nails from the hopper into said tilting section including a switch element for 55 deflecting the nails into the mouth of the raceway, said tilting section tipping automatically after receiving a given number of nails to discharge the same into the remainder of the raceway and operating simultaneously 60 to retract said switch element out of operative position.
- 65 8. A nailing machine comprising, in combination, a nail driving mechanism, a nail hopper, a nail raceway connecting said hopper and driving mechanism and including
- a tilting raceway section communicating directly with the hopper, and means for feeding the nails from the hopper into said tilting section, said tilting section tipping automatically after receiving a given number 70 of nails to discharge the same into the remainder of the raceway, said feeding means including a switch element actuated into and out of operative positions by the movements of said tilting section. 75
9. A nailing machine comprising, in combination, a nail driving mechanism, a nail hopper, a nail raceway connecting said hopper and driving mechanism and including a tilting raceway section constructed and arranged to receive nails from the hopper and be tilted by the weight of a plurality of 80 nails into position to deliver them into the remainder of the raceway, and means operating automatically to latch said tilting section in its raised position. 85
10. A nailing machine comprising, in combination, a nail driving mechanism, a nail hopper, a nail raceway connecting said hopper and driving mechanism and including a 90 tilting section constructed and arranged to receive nails from the hopper and be tilted by the weight of a plurality of nails into position to deliver them into the remainder of the raceway, and means acting to latch said 95 tilting section in its raised position and operating to automatically release said section after a given number of nails has been assembled thereon. 100
11. A nailing machine comprising, in combination, a nail driving mechanism, a nail hopper, a nail raceway connecting said hopper and driving mechanism and including a tilting raceway section constructed 105 and arranged to receive nails from the hopper and be tilted by the weight of a plurality of nails into position to deliver them into the remainder of the raceway, and latch means operating automatically to engage and latch said tilting section in its 110 lowered position. 115
12. A nailing machine comprising, in combination, a nail driving mechanism, a nail hopper, a nail raceway connecting said hopper and driving mechanism and including a tilting raceway section constructed 120 and arranged to receive nails from the hopper and be tilted by the weight of a plurality of nails into position to deliver them into the remainder of the raceway, and means operating automatically to latch said tilting section in its lowered position and thereafter to release said section after all the nails have passed a given point in the raceway. 125
13. A nailing machine comprising, in combination, a nail driving mechanism, a nail hopper, a nail raceway connecting said hopper and driving mechanism and including a tilting raceway section constructed and 130

- arranged to receive nails from the hopper and be tilted by the weight of a plurality of nails into position to deliver them into the remainder of the raceway, and means 5 operating to automatically latch said tilting section at either limit of its movement.
14. A nailing machine comprising, in combination, a nail driving mechanism, a nail hopper, a nail raceway connecting said hopper and driving mechanism and including a tilting raceway section constructed and arranged to receive nails from the hopper and be tilted by the weight of a plurality of nails into position to deliver them 10 into the remainder of the raceway, a latch element acting to latch said tilting section in its raised position, and means operated by engagement with the nails for tripping said latch element and releasing said section.
15. A nailing machine comprising, in combination, a nail driving mechanism, a nail hopper, a nail raceway connecting said hopper and driving mechanism and including a tilting raceway section constructed and arranged to receive nails from the hopper and be tilted by the weight of a plurality of nails into position to deliver them 15 into the remainder of the raceway, a latch element acting to latch said tilting section in its raised position, and means operated by engagement with the nails for tripping said latch element and releasing said section.
16. A nailing machine comprising, in combination, a nail driving mechanism, a nail hopper, a nail raceway connecting said hopper and driving mechanism and including a tilting raceway section constructed and arranged to receive nails from the hopper and be tilted by the weight of a plurality of nails into position to deliver them 20 into the remainder of the raceway, a latch element acting to latch said tilting section in its raised position, and means operated by engagement with the nails for maintaining said latch element operative until after all the nails have passed a given point 25 in the raceway.
17. A nailing machine comprising, in combination, a nail driving mechanism, a nail hopper, a nail raceway connecting said hopper and driving mechanism and including an oscillating raceway section constructed and arranged to receive nails from the hopper and be tilted by the weight of a plurality of nails into position to deliver them 30 into the remainder of the raceway, said oscillating section being provided with a guard extension forming a closure for the passage into the remainder of the raceway during the movement of said oscillating section.
18. A nailing machine comprising, in combination, a nail driving mechanism, a nail hopper provided with a nail raceway 35 to the driving mechanism, and an oscillating element provided with a frictional drive actuated from said nail driving mechanism to transfer the nails singly from said raceway to the driving mechanism.
19. A nailing machine comprising nail driving mechanism, a nail hopper, a nail raceway connecting said hopper and driving mechanism, the outer margin of the hopper bottom being formed with a channel for accommodating the shanks of the nails, a rotary disk resting on the hopper bottom with the edge of said disk overlaying said channel and formed with notches for supporting engagement with the heads of the nails as they traverse the channel, and means for switching the nails from said channel into said raceway.
- In witness whereof I hereto affix my signature.

MAURICE S. FINCH.
